(57) **CLAIM**

The ornamental design for a ducted fan flying machine, as shown and described.

DESCRIPTION

FIG. 1 is a front perspective view of a ducted fan flying machine, showing my new design;

FIG. 2 is a left side view thereof;

FIG. 3 is a right side view thereof;

FIG. 4 is a top view thereof;

FIG. 5 is a front view thereof;

FIG. 6 is a bottom view thereof;

FIG. 7 is a rear view thereof;

FIG. 8 is a left side view of the ducted fan flying machine showing an alternate position of a landing gear, a rear rudder and a left side eleven;

FIG. 9 is a bottom view thereof, showing the alternate position of the landing gear, the rear rudder and the left side eleven;

FIG. 10 is a front view thereof, showing the alternate position of the landing gear and the left side eleven; and, FIG. 11 is a rear view thereof, showing the alternate position of the landing gear, the rear rudder and the left side eleven.

1 Claim, 6 Drawing Sheets---
